COMBINED CUP AND DRINKING TUBE HANDLE

Meyer Saffer, Jamaica, N.Y.

Application July 7, 1959, Serial No. 56,696

Term of patent 14 years

(Cl. D44—9)

FIG.1

FIG.2

FIG.3

FIG.5

Figure 1 is a front side elevational view of a combined cup and drinking tube handle, showing my new design;

Figure 2 is an elevational view thereof as seen from the left-hand side of Figure 1;

Figure 3 is a rear side elevational view thereof;

Figure 4 is a top view thereof; and

Figure 5 is a bottom view thereof.

I claim:

The ornamental design for a combined cup and drinking tube handle, substantially as shown.
